UNITED STATES PATENT OFFICE.

**JOHN WILSON BROWN, JR., OF PHILADELPHIA, PENNSYLVANIA, ASSIGNOR TO THE
ENTERPRISE MANUFACTURING COMPANY OF PENNSYLVANIA, OF PHILADEL-
PHIA, PENNSYLVANIA, A CORPORATION OF PENNSYLVANIA.**

MOLDING-MACHINE.

Specification of Letters Patent. Patented May 12, 1914.

Application filed November 12, 1913. Serial No. 800,608.

To all whom it may concern:

Be it known that I, JOHN W. BROWN, Jr., a citizen of the United States, residing in Philadelphia, Pennsylvania, have invented certain Improvements in Molding-Machines, of which the following is a specification.

of which the following is a specification.

One object of my invention is to provide novel means for transmitting power from a source thereof to the mold supporting table 10 of a molding machine whereby when said table is being jarred in order to compact the sand, its various parts shall be protected from violent and injurious shocks, the arrangements of parts being such that the same mechanism may be employed to vibrate the table, to elevate it, to ram or press the sand in the molds and to draw the patterns from the latter.

20 I further desire to provide novel means for resiliently connecting the pistons of the engines or other source of power for actuating a molding machine, with a mold supporting table of such a machine, together with means whereby certain of said parts are prevented from separating although to some extent they are mechanically independent.

25 These objects and other advantageous ends I secure as hereinafter set forth, reference being had to the accompanying drawings in which:

Figure 1 is a front elevation of a machine constructed according to my invention; Fig. 2 is a plan of the machine shown in Fig. 1; Fig. 3 is an end elevation partly in section on the line $a-a$, Fig. 1; and Fig. 4 is a perspective view of a detail of the invention.

In the above drawings, 1 represents the table-like body of a molding machine which in the present case has an elongated rectangular form, and at its ends is provided with upwardly extending side frame members 2 forming guide-ways for a pair of cross heads 3 to which is trunnioned or pivotally connected a reversible table 4. The upper ends of the guides or members 2 are connected by a top member 2^a whose ends are extended beyond them for the purpose of supporting two cylinders 5. Both of these cylinders are mounted with their longitudinal axes substantially vertical and their closed

ends are connected by a pipe 6 which in turn is connected through a pipe 7 with a controlling valve 8 of suitable construction for governing the flow of motive fluid to and from said cylinders. This valve is supplied with motive fluid from a suitable source through a pipe 9 and I preferably construct it as described and claimed in my application for U. S. patent filed of even date herewith, Serial No. 800,609. Each of the cylinders 5 is open at its lower end and contains a piston or plunger 10 of the trunk type, packed by a suitable gland 11 and the necessary packing material.

Mounted in suitable bearings 12 carried by the base plate 13 of the machine is a horizontally extending shaft 14 on which are loosely mounted two crank arms 15 respectively connected to the pistons 10 of the two cylinders by rods 16. On either side of each of these cranks are mounted the two members of a second crank 17 to whose crank pin 18 is attached one end of a rod 19 whose second end engages the trunnion 20 of one of the cross heads 3. The adjacent outer portions of the cranks 15 and 17 of each set are made flat or plane, and between them is mounted a block 21 of rubber or equivalent resilient material. The outer portions of the two cranks of each set are prevented from separating by a connecting bolt 22 which, however, does not prevent them from moving together when the rubber block 21 is compressed.

At opposite ends of the body 1 are mounted 85 vertical spindles 23 serving respectively as hinges or pivots for swinging tables 24. When these tables are positioned as shown in Fig. 1 they normally rest upon suitably formed portions of the upper surface of the body 1, although they may be raised clear of this when desired by means of a shaft 25 supported in suitable bearings at its ends and provided with cams 26 each of which is designed to act upon one end of a lever 27 95 fulcrumed on the frame and engaging a portion of the table structure 24 adjacent its vertical spindle 23. An operating arm 28 is provided for the shaft 25 and the cams 26 are so set that when this arm is forced down, 100

both swinging tables 24 are raised clear of the body 1 and may be swung outwardly on their spindles 23.

Mounted upon the shaft 14 are a pair of 5 coil springs 29 one end of each of which is fixed to a collar 30 having clutch teeth designed to operatively engage the similarly formed teeth of the other collar 31 keyed or otherwise suitably fixed to the shaft 14.

10 These springs are so designed and set that through the crank arms 17 and their associated parts they at all times tend to move the table 4 and pistons 10 to and maintain them in their uppermost positions even 15 though said table be fully loaded.

Under conditions of use the table 4 has fastened upon it one or more sets of patterns and after it has been swung on its trunnions 20 by means of handles 32 through an angle 20 of 180° into the position shown in dotted lines, suitable flasks are mounted on the patterns. When it is desired to compact the sand in the flasks, the valve 8 is so manipulated that motive fluid such as compressed air is alternately supplied to and exhausted from the cylinders 5 with the result that through the rods 16, crank arms 15 and rubber blocks 21, the crank arms 17, the rods 19 and the table 4 are alternately moved 25

30 down against the action of the springs 29 so that said table strikes the body, being thereafter caused to rise by the action of said springs, with the result that the flasks are more or less violently jarred, thus acting on 35 the sand as desired. Under these conditions the rubber blocks act to prevent the transmission of injurious shocks to the engine mechanism and also prevent the otherwise rapid wear of the connections between said

40 parts. After the jarring or compacting operation has been continued for a suitable time, the valve is actuated to cut off the motive fluid and the parts of the mold are properly connected to each other and to the table 45

45 4, which is raised to its upper position and reversed. By proper operation of the valve 8 the engines may be caused to lower the table, thus confining the parts of the mold between the latter and the tables 24 and

50 50 strongly compressing the sand therein in the well known manner. Thereafter the valve 3 may be operated to cause the engine to raise said table and the patterns may be withdrawn. By pressing down the operating arm 28, a partial revolution may be then given to the shaft 25 with the result that the cams 26 and levers 27 are actuated and caused to raise the swinging tables, clear of the parts of the frame on which they are

55 60 supported and said tables may be swung outwardly on their vertical spindles 23 to permit the finished molds to be removed.

I claim:

1. The combination in a molding machine

of a source of power; a movably mounted support for a mold; and mechanism, including a resilient shock absorbing member operatively connecting said power source with said support.

2. The combination in a molding machine of a source of power; a movably mounted support for a mold; and mechanism operatively connecting said power source with said support; the same including two cranks; and a resilient member operatively connecting said cranks for transmitting power between them.

3. The combination in a molding machine of a source of power; a movably mounted support for a mold; and mechanism operatively connecting said power source with said support; the same including two cranks, and a body of resilient material mounted between opposed portions of said cranks.

4. The combination in a molding machine of a source of power; a movably mounted support for a mold; a supporting shaft; two cranks on the shaft, one loose and the other fixed to the shaft; a resilient member connecting the outer portions of said cranks; and rods connecting the end portions of the cranks respectively with the power source and with the mold support.

5. The combination in a molding machine of a source of power; a movably mounted support for a mold; a supporting shaft; two cranks on the shaft, one loose and the other fixed to the shaft; a resilient member mounted between the outer portions of said cranks; rods connecting the ends of the cranks respectively with the power source and with the mold support; with means for limiting the possible separation of said cranks.

6. The combination in a molding machine of two sources of power; a movably mounted support for a mold; and mechanism operatively connecting said power sources with said support, the same including two pairs of cranks; resilient members respectively mounted between the cranks of each pair; and members connecting the cranks of each pair respectively with the mold support and with one of the power sources.

7. The combination in a molding machine of two sources of power; a movably mounted support for a mold; and mechanism operatively connecting said power sources with said support, the same including two pairs of cranks; resilient members respectively mounted between the cranks of each pair; members connecting the cranks of each pair respectively with the mold support and with one of the power sources; with a spring or springs acting on the cranks in opposition to the power source.

8. The combination in a molding machine of a source of power; a movably mounted support for a mold; a shaft; a crank fixed

thereto; a member connecting said crank with the source of power; a spring acting on the shaft in opposition to said power source; a second crank loose on the shaft; a 5 bar connecting said second crank to the mold support; and a resilient member mounted between the two cranks.

In testimony whereof, I have signed my name to this specification, in the presence of two subscribing witnesses.

JOHN WILSON BROWN, Jr.
